(57) **CLAIM**

The ornamental design for a VR / AR glasses, as shown and described.

DESCRIPTION

FIG. 1 is a front view of an ornamental design for a VR / AR glasses showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is a folding state view thereof.

The oblique line shading in FIGS. 1, 3-4 and 6-8 represents transparency or translucency.

1 Claim, 8 Drawing Sheets
